CLAIM

The ornamental design for a food containing package with integral handle, as shown and described.

DESCRIPTION

FIG. 1 is a top plan view of a food containing package with integral handle showing my new design;

FIG. 2 is a front elevational view thereof, the undisclosed opposite side being a mirror image;

FIG. 3 is a right side elevational view thereof;

FIG. 4 is a top perspective view thereof;

FIG. 5 is a bottom plan view thereof;

FIG. 6 is a left side elevational view thereof; and,

FIG. 7 is a left side elevational view of a second embodiment of the package in FIG. 1.

FIG. 3

FIG. 4

FIG. 1

FIG. 2

FIG. 5

FIG. 7

FIG. 6
